US00D947194S

(12) **United States Design Patent** (10) **Patent No.:** **US D947,194 S**
(45) **Date of Patent:** **** Mar. 29, 2022**

(54) **CONTROLLER**

(71) Applicant: **Ganzhou Yuanjia Technology Development Co., Ltd.**, Ganzhou (CN)

(72) Inventor: **Yuechun He**, Ganzhou (CN)

(73) Assignee: **GANZHOU YUANJIA TECHNOLOGY DEVELOPMENT CO., LTD.**, Shangyou (CN)

(**) Term: **15 Years**

(21) Appl. No.: **29/652,325**

(22) Filed: **Jul. 21, 2020**

(51) LOC (13) Cl. **14-02**

(52) U.S. Cl.

USPC **D14/433**

(58) **Field of Classification Search**

USPC D14/356, 432-434, 453, 454, 511, 203.8, D14/209.1, 238.1, 240, 125; 439/638, 439/928, 105, 502; 710/303, 304; 361/679.41, 679.55, 679.56; D13/110, D13/133, 146

CPC H01R 13/71; H01R 13/6271; H01R 24/62; H01R 13/652

(57) **CLAIM**

The ornamental design for a controller, as shown and described.

DESCRIPTION

FIG. 1 is a left elevation view of a controller, showing my new design;

FIG. 2 is a top plan view thereof;

FIG. 3 is a rear elevation view thereof;

FIG. 4 is a top perspective view thereof;

FIG. 5 is a bottom perspective view thereof;

FIG. 6 is a bottom plan view thereof;

FIG. 7 is a front elevation view thereof; and,

FIG. 8 is a right elevation view thereof.

The broken lines in the Figures show portions of the controller which form no part of the claimed design.

1 Claim, 8 Drawing Sheets
